UNITED STATES PATENT OFFICE

2,455,872

CYLINDRICAL DOMESTIC REFRIGERATOR

Willard L. Morrison, Lake Forest, Ill.

Application May 26, 1945, Serial No. 596,048

16 Claims. (Cl. 62—116)

1

This invention relates to refrigerating apparatus and has for one purpose to provide an improved evaporator.

Another purpose is to provide an evaporator which circumferentially defines and surrounds an open topped storage area.

Another purpose is to provide an evaporator which shall be economical and simple to manufacture.

Another purpose is to provide an evaporator unit which permits the employment of a minimum volume of a volatile refrigerant.

Another purpose is to provide an evaporator surrounding a storage space, which evaporator distributes the volatile evaporant substantially uniformly throughout the area of the evaporator which surrounds the storage space.

Another purpose is to provide improved means for maintaining a high temperature about the top of the unit, above the evaporator where it is contacted by warm outside air, at a line of demarcation between chilled and not chilled areas.

Another purpose is to provide an evaporator structure which includes a receiver.

Another purpose is to provide an evaporator container, which may be made of two generally cylindrical members, which, together, define both an evaporator and a receiver, the inner of the two members forming the storage space of the refrigerator.

Other purposes will appear from time to time in the course of the specification and claims.

I illustrate the invention more or less diagrammatically in the accompanying drawings, wherein—

Figure 1 is a side elevation;

Figure 2 is a section, on an enlarged scale, on the line 2—2 of Figure 1;

Figure 3 is a section on the line 3—3 of Figure 2;

Figure 4 is a section on the line 4—4 of Figure 3;

Figure 5 is a section on the line 5—5 of Figure 2;

Figure 6 is a section on the line 6—6 of Figure 2; and

Figure 7 is a vertical axial section, on an enlarged scale, illustrating a variant form of evaporator and receiver structure.

Like parts are indicated by like characters throughout the specification and drawings.

In the invention herein illustrated, I employ a base 1 which may be generally flat and shown as having a generally plane top surface 2 and a generally plane bottom surface 3 mounted on

2

skids 4. The evaporator is illustrated as having an outer cylinder 5 and an inner cylinder 6. The inner and outer cylinders may be welded or otherwise secured to each other at their upper and lower edges as shown in Figures 3, 5 and 6 at 7 and 8. I may for example employ seam welding. The cylinders in the completed container or evaporator, are spaced sufficiently apart to define a refrigerant receiving space which extends entirely about the evaporator and substantially from top to bottom of the evaporator. This may be a space of very low clearance. It may for example approximate .026" to .028", this being given as an example rather than as a rigid restriction to any particular space range. The point is that it is practical, in the present structure, to employ a close clearance between the two cylinders.

In the form of the device herein shown, the inner cylinder 6 is shown as substantially a true cylinder although it might be slightly tapered and has a smooth, preferably unbroken cylindrical face which circumferentially surrounds and defines the storage space of the refrigerator unit. The outer cylinder is provided with two outer beads or concavo-convex projections 9, 10. These serve as distributors for the refrigerant which is shown as entering the bottom inlet passage 11 and escaping through the top outlet passage 12.

I illustrate the upper distributor 9 as substantially larger than the lower distributor 10 because it receives gas whereas the bottom distributor receives the refrigerant as an unexpanded liquid. The two cylinders may be spaced apart by the indented projections 13 on the outer cylinder, of which any suitable number may be employed for providing a uniform effective spacing between the two cylinders and may also employ intermediate smaller distributor beads as shown at 14 which are shown as extending entirely about the outer cylinder. One or more may be employed, depending upon the height of the evaporator.

After the two cylinders have been formed and joined, I may apply any suitable bottom member 15 with its centering projection 15a, which may be welded to the cylinders as at 16.

I may find it advantageous to roll both the inner and the outer cylinder from sheet stock. They may be rolled into substantially correct form and dimensions and may then be seam welded or otherwise secured at their abutting edges. In forming the outer cylinder 5, I find it advantageous to pass the sheet stock through forming rolls

which roll out the manifolds or distributors 9, 10 and 14, and which also form the dimples or spacing indentations 13, at the same time the integral heat interchanger 5a is formed at the top of the outer cylinder. Since the forming tools do not of themselves form part of the present invention, I do not illustrate them. It will be understood, however, that I may employ any suitable forming rolls or forming tools for producing requisite shape or form of the two cylinders. After the two cylinders have been initially formed, the inner cylinder and the outer cylinder are interfitted. For ease of interfitting and for accuracy of manufacture, I find it desirable initially to form the cylinders with a somewhat larger clearance than their final clearance. Thereafter and preferably before they are permanently secured together, I may employ any suitable internal expander for directing a substantially uniform outward thrust throughout the area of the inner face of the inner cylinder 6. The thrust is continued until the inner cylinder engages the dimples 13 which provide means for uniformly spacing the two cylinders apart. Whereas I have illustrated and described the use of spacing dimples integral with the outer cylinder 5, it will be understood that any other suitable spacing means may be employed. Or under some circumstances, the spacing means may be dispensed with although they constitute an efficient mode of obtaining a uniform clearance between the inner face of the outer cylinder 5 and the outer face of the inner cylinder 6. Thus when the expanding tool causes the inner cylinder 6 to engage the points of the dimples 13, then the two cylinders are properly spaced. The forming tool forms the parts to a true cylinder.

It will be noted that the distributors 9 and 10 are spaced somewhat inwardly of the edges of the cylinders. Also the integral interchanger 5a, which is shown as above the top distributor 9, is spaced somewhat downwardly from the upper edge of the final cylindrical structure. This is advantageous as giving adequate space for seam welding at the points 1 and 8. The distributors or manifolds so placed do not interfere with the use of a wheel type seam welder. The two cylinders are also seam welded at 1a between the heat interchanger 5a and distributor 9. Either during the last welding operation or directly afterwards, I may add the bottom element 15. Any suitable form of bottom may be employed. I may for example employ a drawn cup bottom. However, the bottom may be added either before or after or at the time of welding the two cylinders 5 and 6.

It will be understood that whereas I find it convenient and economical to form the outer and inner cylinders 5 and 6 of sheet stock, welded along a longitudinal seam, I may also employ drawn cylinders. For example, it is under some circumstances advantageous to draw the inner cylinder in order to have it seamless. In that event the bottom may be integral with the inner cylinder and the inner cylinder will be outwardly expanded against the outer cylinder, the welding following the final expansion.

It will be understood that under some circumstances it may be advantageous to weld the cylinders together at top and bottom before the final expansion of the inner cylinder in relation to the outer, takes place.

The refrigerating cycle and structure do not of themselves form a part of the present invention. Any suitable refrigerating apparatus may be used. In the drawings I have illustrated a refrig-

erating apparatus comprising a motor 22 and a compressor 23, driven from the motor by a belt 24. The gas, when compressed by the compressor, passes out through the pipe 38 and is then delivered to the top of the condenser 39. The liquid then passes from the condenser through the pipe 40 into the receiver 41. The refrigerant then passes from the receiver 41 by the duct 42 to the integral heat exchanger 5a which is formed between the inner and outer cylinders 5 and 6. The refrigerant passes around this heat interchanger and after having passed about almost 360 degrees, it flows along the passage 10c to any suitable expansion valve 52 with any suitable thermostatic control 54. The refrigerant, now at low pressure, passes along the duct 11 to the lower distributor or manifold 10 of the outer cylinder 5. The discharge passage 12 returns the gas from the upper enlargement or distributor 9 to the compressor.

The compressor-condenser unit may be mounted upon a lateral extension 1a of the base 1 and may be surrounded by any suitable housing 60. The evaporator is shown as positioned and supported on a block or disc 61 of insulating material, which is initially held against lateral movement on the base 1 by the dowel 62. The member 61 is recessed to receive the centering projection 15a. 63 is any suitable concentric surrounding housing which constitutes the exterior wall of the refrigerator cabinet. It may be of relatively thin relatively flexible material, such as sheet metal. When the insulation 64 is crowded down into the space between the evaporator and the outer wall 63, a firm structure is provided which surrounds and is reinforced by the evaporator. Any suitable top cover 65 may be employed for the insulation and a removable top closure 66 is used to protect the storage area from above. Any suitable insulation 67 may surround the upper portion of the evaporator care being taken to avoid the use of any heat transmitting material. The cover 66 is at all points located above the space surrounded by the evaporator and does not extend down into the pool of cold air which is maintained in the space surrounded by the evaporator.

Referring to Fig. 7, I illustrate a variant form of evaporator in which the receiver is formed as part of the evaporator structure. Thus I illustrate an inside cylinder 6a and an outside cylinder 50. In the outside cylinder I form the upper distributor 9a and the lower distributor 10a. Any suitable spacing means 13a may be employed to separate the two cylinders to form the evaporator space. I may also employ intermediate distributors 14a, which may also be formed in the outer cylinder. Above the upper distributor 9a, I illustrate a heat exchanger 5b. Below the lower distributor 10a I extend the inner cylinder 6a as at 6b to a level below the bottom 15b, and I outwardly expand the outer cylinder 50 as at 10b, to form a circumferential receiver. This receiver is connected by the duct 10a with the heat exchanger 5b. The duct 40a extends from the condenser directly to the receiver about the bottom of the combined evaporator receiver structure. It will be understood that whereas I have shown the various projections employed to form the receiver, distributors and heat exchanger as extending outwardly from the outer cylinder, I may also form the various members either by inwardly deforming the inner cylinder 6a alone or by deforming both cylinders, instead of outwardly deforming the outward cylinder. However, it is advantageous to maintain the inner member sub-

stantially cylindrical, and to deform the outer cylinder instead. Note that the bottom 15b of Fig. 7 is located above the level of the receiver 10a. It will be understood that while the height of the bottom may be varied, the arrangement shown in Fig. 7 is advantageous. In the form of Fig. 7 note that the insulating disc 61a fills the space within the lower end of the cylindrical structure and is cut down outwardly and provided with a thin circumferential portion 61b which underlies the relatively loose insulation 64a. It may not be necessary to employ the downward extension 15a of the bottom 15.

Note that all joints or sealing lines between the two cylinders 5a and 6a may be obtained by welding. Thus although only two parts, the inner and outer cylinders, need not be employed, they are so connected as to provide a series of entirely separated chambers including the receiver 10a at the bottom, the evaporator space, the upper and lower distributors, and finally the heat interchanger 5b at the top.

Referring to the form of the evaporator it may be varied substantially within the scope of my invention. Since the upper distributor 9 must accommodate evaporated refrigerant, it is shown as larger than the bottom distributor 10. The details of the spacers 13 may be widely varied and I may for example employ ridges or projections of other form.

It is immaterial whether the projections 13 and the intermediate distributors 14 are formed in the inner or in the outer cylinder. It will be understood that it may be advantageous to have the inner surface of the inner cylinder cylindrical and flush. But the distributors 9 and 10, the intermediate spacers 13, the intermediate distributors 14, and the heat exchanger 5a and the receiver 10a may some or all of them be formed in the inner rather than in the outer cylinder, if desired.

It will be realized that whereas I have described and shown a practical and operative device, nevertheless many changes may be made in the size, shape, number and disposition of parts without departing from the spirit of my invention. I therefore wish my drawings and description to be taken as in a broad sense illustrative and diagrammatic.

The use and operation of my invention are as follows:

I provide an evaporator structure for refrigerators which circumferentially defines and surrounds a storage space. In the use of the device herein shown, the storage space may be employed to receive and store foods or other substances. It may be cooled sufficiently to treat materials, such as metals, where cold temperature treatment is desired.

I provide an evaporator structure which has an effective cooling surface throughout its entire inner area. The relation between the cooled area of the evaporator and the volume of the space cooled is such that I obtain a substantial avoidance of any temperature differential between the stored material and the refrigerant which would be effective to cause thermosyphonic action. This is particularly important in connection with the storage of food stuffs, such as meats. The result is an avoidance of deterioration or desiccation of the stored substances and the reduction to a minimum of the depth of frost on the inner surface of the evaporator.

I also provide an evaporator which is economical to manufacture, which is highly efficient in

operation and which constitutes an adequate central frame or support or skeleton for the refrigerator. The outer and inner cylinders 5 and 6 may be truly cylindrical or they may be slightly tapered. They may be integrally drawn, or one or both of them may be rolled from sheet and formed with welded abutting edges. It will be seen that I combine in a single structure, including a pair of concentric and generally cylindrical members, an open topped storage container, a heat interchanger, a receiver and an evaporator. The result is an efficient, strong unit which is cheap to manufacture and sturdy in use, and which serves as the skeleton or framework of the completed refrigerator.

In the actual manufacture of the device after the two cylinders have been formed, they are interfitted or telescoped and are secured together at their upper and lower edges, and are provided with an accurate clearance and proper final form by the expansion of the inner cylinder 6 in relation to the outer cylinder 5. Any suitable spacing means may be employed but I find the integral dimples 13 highly efficient.

In the device of Figure 3, the refrigerant in liquid unexpanded form, flows along the inlet 11 to the bottom distributor or manifold 10, which receives a substantial volume of the liquid. In the course of its evaporation, the refrigerant rises upwardly about the entire outer circumference of the inner cylinder 6. The spacers 13 are of insufficient area to interfere with this upward rise. The top manifold or distributor 9 receives the refrigerant in evaporated or gaseous form and the gas passes off through the discharge outlet 12. I find that the intermediate and preferably smaller distributors 14 are of assistance in maintaining the uniform distribution of the refrigerant.

In the preferred form of Fig. 7, the refrigerant flows in passage 40a from the condenser directly to the receiver 10b which forms part of the cylindrical structure and is housed within the insulation 64a. Liquid refrigerant flows thence along the passage 10d to the heat interchanger 5a. The object of passing the relatively warm liquid about the top of the cylinder is to keep the rim of the cylinder at a higher temperature than the portion immediately below, to delay in part the formation of frost thereon. In fact, it is advantageous if the extreme upper edge portion of the cylinder is actually warmer than the air which contacts it. Under those circumstances it tends to have less attraction for moisture from outside air than would be the case if the top rim were as cool as the rest of the cylinder. It is at this point that I contact the cylinder with an insulating member as shown for example at 80. From the heat interchanger 5a the refrigerant flows to any suitable expansion valve 52a and thence by the passage 11a to the lower distributor 10a. Finally the evaporated refrigerant flows from the upper distributor 9a back to the compressor along the duct 12a.

It will be understood that there is no metal path of heat transmission between the outer covering 63 and the evaporator structure. The member 65 may for example be formed of some suitable insulating material. Beneath it and between it and the insulation body 67 is a member of insulating material 80.

I claim:

1. In an open topped evaporator and storage structure for refrigerators, concentric generally vertically axised inner and outer cylinders having spacing means adapted to space them slightly

apart, said cylinders being sealed together adjacent their ends to define therebetween an evaporator space, a bottom member closing the storage space surrounded by the evaporator space thus formed, said cylindrical members being additionally separated adjacent their upper ends to provide a generally circumferentially extending heat interchanger space, means for delivering a liquid refrigerant to said heat interchanger space and thence to said evaporator, and means for withdrawing evaporated refrigerant from the evaporator.

2. In an open topped evaporator and storage structure for refrigerators, concentric generally vertically axised inner and outer cylinders having spacing means adapted to space them slightly apart, said cylinders being sealed together adjacent their ends to define therebetween an evaporator space, a bottom member closing the storage space surrounded by the evaporator space thus formed, said cylindrical members being additionally separated adjacent their upper ends to provide a generally circumferentially extending heat interchanger space, means for delivering a liquid refrigerant to said heat interchanger space and thence to said evaporator, and means for withdrawing evaporated refrigerant from the evaporator, the inner cylinder being generally cylindrical throughout, the outer cylinder having formed therein an outwardly extending portion defining said heat interchanger space.

3. In an open topped evaporator and storage structure for refrigerators, concentric generally vertically axised inner and outer cylinders having spacing means adapted to space them slightly apart, said cylinders being sealed together adjacent their ends to define therebetween an evaporator space, a bottom member closing the storage space surrounded by the evaporator space thus formed, said cylindrical members being separated adjacent their upper and lower ends to provide circumferential distributors in communication with said evaporator space and being additionally separated adjacent their upper ends to provide a generally circumferentially extending heat interchanger space, means for delivering a liquid refrigerant into said heat interchanger space and thence to one of the distributors of said evaporator and means for withdrawing the evaporated refrigerant from the opposite distributor of the evaporator.

4. In an open topped evaporator and storage structure for refrigerators, concentric generally vertically axised inner and outer cylinders having spacing means adapted to space them slightly apart, said cylinders being sealed together to define therebetween an evaporator space, a bottom member closing the storage space surrounded by the evaporator space thus formed, said cylindrical members being additionally separated and sealed together adjacent their lower ends to provide a generally circumferentially extending receiver, passage means for delivering liquid refrigerant to the receiver, and from the receiver to said evaporator space, and means for withdrawing evaporated refrigerant from the evaporator.

5. In an evaporator and storage structure for refrigerators, generally concentric inner and outer cylindrical members spaced apart and sealed together to define between them a circumferentially extending evaporator, and a circumferentially extending receiver, and a bottom element immediately above the receiver, the top of said structure being open to provide an open topped storage space.

6. In an evaporator and storage structure for refrigerators, generally concentric inner and outer cylindrical members spaced apart and sealed together to define between them a circumferentially extending evaporator, and a circumferentially extending receiver, and a bottom element for said structure, the top of said structure being open to provide an open topped storage space, said receiver being located below the level of said bottom element.

7. In an evaporator and storage structure for refrigerators, generally concentric inner and outer cylindrical members spaced apart and sealed together to define between them a circumferentially extending evaporator, and a circumferentially extending heat exchanger, and a bottom element for said structure, the top of said structure being open to provide an open topped storage space, said heat exchanger being located adjacent the upper edge of the storage structure.

8. In an evaporator and storage structure for refrigerators, an open topped storage member including a generally cylindrical evaporator, means for withdrawing evaporated refrigerant from said evaporator and means for delivering refrigerant to said evaporator including a heat exchanger extending about the upper edge of said evaporator and adapted to maintain the upper edge of the storage member at a relatively high temperature.

9. In an evaporator and storage structure for refrigerators, an open topped storage member including a generally cylindrical evaporator and a bottom wall, a heat interchanger formed unitarily with said evaporator, a receiver formed unitarily with said evaporator, means for delivering a liquid refrigerant to said receiver, means for delivering liquid refrigerant from said receiver to said heat interchanger, means, including pressure reducing means, for delivering refrigerant to said evaporator and means for withdrawing evaporated refrigerant from said evaporator.

10. In an evaporator and storage structure for refrigerators, an open topped storage member including a generally cylindrical evaporator and a bottom wall, a heat interchanger formed unitarily with said evaporator, a receiver formed unitarily with said evaporator, means for delivering a liquid refrigerant to said receiver, means for delivering liquid refrigerant from said receiver to said heat interchanger, means, including pressure reducing means, for delivering refrigerant to said evaporator and means for withdrawing evaporated refrigerant from said evaporator, and a body of insulation surrounding said evaporator and said receiver.

11. In a refrigerator, a base, an evaporator and storage structure, defining an open topped storage zone, mounted on said base and including a generally cylindrical evaporator and a bottom wall, a heat interchanger and a receiver formed unitarily with said evaporator, and a refrigerant mechanism and circuit including a motor-compressor-condenser unit mounted on said base, a duct extending from the condenser to the receiver, a duct extending from the receiver to the heat interchanger, a duct extending from the heat interchanger to the evaporator, pressure reducing means in the line of delivery of said duct, and a return duct extending from the evaporator to the compressor.

12. In a refrigerator, a base, an evaporator and storage structure, defining an open topped storage zone, mounted on said base and including a gen-

erally cylindrical evaporator and a bottom wall, a receiver formed unitarily with said evaporator, a refrigerant mechanism and circuit, including a motor-compressor-condenser unit mounted on said base, a duct extending from the condenser to the receiver, a duct extending from the receiver to the evaporator, pressure reducing means in the line of delivery of said duct, and a return duct extending from the evaporator to the compressor.

13. In a refrigerator, a base, an evaporator and storage structure, defining an open topped storage zone, mounted on said base and including a generally cylindrical evaporator and a bottom wall, a heat interchanger and a receiver formed unitarily with said evaporator, and a refrigerant mechanism and circuit including a motor-compressor-condenser unit mounted on said base, a duct extending from the condenser to the heat interchanger, a duct from the receiver to the heat interchanger, a duct extending from the heat interchanger to the evaporator, pressure reducing means in the line of delivery of said duct, and a return duct extending from the evaporator to the compressor, a layer of insulating material between said base and said evaporator and storage structure, upon which said evaporator and storage structure rests, a layer of insulating material surrounding said evaporator and storage structure, an outer generally cylindrical housing surrounding said insulating layer, said evaporator and storage structure constituting the reinforcement and support for said insulating layer and outer housing.

14. In a refrigerator, a base, an evaporator and storage structure, defining an open topped storage zone, mounted on said base and including a generally cylindrical evaporator and a bottom wall, a receiver formed unitarily with said evaporator, a refrigerant mechanism and circuit, including a motor-compressor-condenser unit mounted on said base, a duct extending from the condenser to the receiver, a duct extending from the receiver to the evaporator, pressure reducing means in the line of delivery of said duct, and a return duct extending from the evaporator to the compressor, a layer of insulating material between

said base and said evaporator and storage structure, upon which said evaporator and storage structure rests, a layer of insulating material surrounding said evaporator and storage structure, an outer generally cylindrical housing surrounding said insulating layer, said evaporator and storage structure constituting the reinforcement and support for said insulating layer and outer housing.

- 10 15. In a refrigerator, an open topped evaporator-storage element adapted to surround a storage space, insulation means extending beneath and about said element, means for circulating a volatile refrigerant through the evaporator component of said element, a removable cover for said element and means for heating the upper edge of said element, at a level above the evaporator component and for thereby reducing frosting.
- 15 20. In a refrigerator, an open topped evaporator-storage element adapted to surround a storage space, insulation means extending beneath and about said element, means for circulating a volatile refrigerant through the evaporator component of said element, a removable cover for said element and means for heating the upper edge of said element, at a level above the evaporator component and for thereby reducing frosting.
- 20 25. In a refrigerator, an open topped evaporator-storage element adapted to surround a storage space, insulation means extending beneath and about said element, means for circulating a volatile refrigerant through the evaporator component of said element, a removable cover for said element and means for heating the upper edge of said element, at a level above the evaporator component and for thereby reducing frosting, said means including a heat interchanger, in the line of delivery of refrigerant to the evaporator, extending about the upper edge of said element.
- 25 30. In a refrigerator, an open topped evaporator-storage element adapted to surround a storage space, insulation means extending beneath and about said element, means for circulating a volatile refrigerant through the evaporator component of said element, a removable cover for said element and means for heating the upper edge of said element, at a level above the evaporator component and for thereby reducing frosting, said means including a heat interchanger, in the line of delivery of refrigerant to the evaporator, extending about the upper edge of said element.

WILLARD L. MORRISON.
